(57) **CLAIM**

The ornamental design for a display screen with animated graphical user interface, as shown and described.

DESCRIPTION

FIG. 1 is a front view of a first image in a sequence of a display screen with animated graphical user interface, showing the claimed design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is an enlarged front view of a detail indicated in FIG. 13, provided for clarity of illustration;

FIG. 15 is another enlarged front view of a detail indicated in FIG. 13, provided for clarity of illustration;

FIG. 16 is another enlarged front view of a detail indicated in FIG. 13, provided for clarity of illustration;

FIG. 17 is a front view of a fourteenth image thereof;

FIG. 18 is an enlarged front view of a detail indicated in FIG. 17, provided for clarity of illustration;

FIG. 19 is another enlarged front view of a detail indicated in FIG. 17, provided for clarity of illustration;

FIG. 20 is another enlarged front view of a detail indicated in FIG. 17, provided for clarity of illustration;

FIG. 21 is another enlarged front view of a detail indicated in FIG. 17, provided for clarity of illustration;

FIG. 22 is a front view of a fifteenth image thereof;

FIG. 23 is a front view of a sixteenth image thereof;

FIG. 24 is a front view of a seventeenth image thereof;

FIG. 25 is an enlarged front view of a detail indicated in FIG. 24, provided for clarity of illustration;

FIG. 26 is another enlarged front view of a detail indicated in FIG. 24, provided for clarity of illustration;

(Continued)

FIG. 27 is another enlarged front view of a detail indicated in FIG. 24, provided for clarity of illustration; FIG. 28 is a front view of an eighteenth image thereof; FIG. 29 is a front view of a nineteenth image thereof; FIG. 30 is an enlarged front view of a detail indicated in FIG. 29, provided for clarity of illustration; FIG. 31 is another enlarged front view of a detail indicated in FIG. 29, provided for clarity of illustration; FIG. 32 is a front view of a twentieth image thereof; FIG. 33 is a front view of a twenty first image thereof; FIG. 34 is a front view of a twenty second image thereof; FIG. 35 is an enlarged front view of a detail indicated in FIG. 34, provided for clarity of illustration; FIG. 36 is another enlarged front view of a detail indicated in FIG. 34, provided for clarity of illustration; FIG. 37 is another enlarged front view of a detail indicated in FIG. 34, provided for clarity of illustration; and, FIG. 38 is another enlarged front view of a detail indicated in FIG. 34, provided for clarity of illustration.

The appearance of the display screen with animated graphical user interface sequentially transitions between the images shown in FIGS. 1-13, 17, 22-24, 28, 29 and 32-34. The process or period in which one image transitions to another image forms no part of the claimed design. The dot-dash broken lines illustrate the display screen and form no part of the claimed design. The remaining broken lines illustrate portions of the graphical user interface that form no part of the claimed design.

FIG. 5

Tips For Your Plants

Tip 1

Water Them Adequately
Your Spathiphyllum, Peace Lily, Pothos Ivy need water more frequently. Ensure that the soil around the plant stays moist, as the water tends to evaporate rapidly and reduces the humidity in which this plant thrives.

This tip applies to the following plants of yours as well: Spathiphyllum, Peace Lily

Tip 2

Remove Crossing/Rubbing Branches
Midsummer is when your Weeping Fig have a short dormitory season, so it's the perfect time to prune this tree to help it maintain its shape. Cut away unruly, dead, or diseased branches during this season.

This tip applies to the following plant of yours as well: Spathiphyllum

Tip 3

Expose Them into the sunlight and heat
Please let your Corn plants like bamboo get the after sunlight in the morning. You can also use shade nets to help them cool down. And remember to water them in time as the hot weather stimulates the transpiring process.

This tip applies to the following plant of yours as well: Spathiphyllum

Care Tips

Water | Every week

Golden pothos grows best in moist soil with medium humidity. When growing golden pothos, it is beneficial to mist the plant's leaves regularly with a spray bottle to maintain humidity around the leaf area. The top layer of soil should be allowed to dry between waterings, and the plant will grow best if it is kept in a pot with a draining hole in the bottom.

Fertilizing | Every week

Fertilization once a month during the growing season.

Pruning | Every week

Shape the plant every 2 months

Golden pothos

Epipremnum aureum

Overview

The golden pothos is a popular flowering house plant that's commonly seen in Australia, Asia, and the West Indies. It goes by many nicknames, including "devil's ivy," because it is so hard to kill, and can grow in the dark. Golden pothos has poisonous sap, so it should be kept away from pets and children.

FIG. 18

Name Story

Golden pothos

Since its green leaves are faced with the color gold, it is called Golden Pothos. *Epipremnum aureum* has a long and tortuous naming history, and it has been reclassified several times. It was first classified as *Pothos aureus*. In 1963, scholars discovered that it actually had a binomial name. Since then, scholars closely observed and investigated the plant's

[Show More ↴](#)

Interesting Facts

The golden pothos is a popular houseplant, largely due to the way in which it cleans the air. In newly-renovated homes, the golden pothos has been shown to absorb benzene, trichloroethylene and formaldehyde, although you cannot rely on the plant alone to remove all harmful gases from a room. Nevertheless, they have tremendous vitality.

Environmental Protection Value The golden pothos is a popular flowering houseplant that's commonly seen in Australia, Asia, and the West Indies. It goes by many nicknames, including "devil's ivy," because it is so hard to kill, and can grow in the dark. Golden pothos has poisonous sap, so it should be kept away from pets and children.

Garden Use Golden pothos is a perennial evergreen vine commonly found in gardens of tropical climates. It is prized for its variegated green and yellow leaves. The trailing habit makes it suitable for ground cover or as an understory plant. Golden pothos is essential in tropical-themed gardens. Plant with ferns for textural contrast or other succulents for a beautiful scene.

Marble Queen Pothos... See more

Epipremnum aureum 'Marble Queen' is a devil's ivy cultivar that's quite similar in appearance to another popular variety, the 'Golden Pothos'. What sets these two apart is that the variegated, marbled pattern in Marble Queen pothos's foliage is usually a mix of white and green, rather than yellow and green.

Preventions

It's always easier to prevent diseases than
to treat them.

① Pay attention in case of high
humidity

Plant diseases are more likely to occur
when the humidity is high. Leaf spot can
be avoided by applying fungicides to
plants before a prolonged downpour

② Check for pests regularly

Pests can spread disease over long
distance, so look for hidden areas such as
leaf underside;

FIG. 26

Infection

- It spreads among all plants
- Reservoirs
Air, water, tools

Infection Prevention

- Check for the same or similar symptoms appear on the surrounding plants.
- If any leaf spots appear, cut off infected areas and apply fungicide as well.
- Note that these wasted branches and leaves cannot be composted or turned into soil as they may still spread the disease.

Common Problems

Leaf Spot

Anthracnose

Root Rot
